UNITED STATES PATENT OFFICE

2,130,711

GRINDING WHEEL TRUING DEVICE

Harry Hales Asbridge, Moss Lane, Ashton-on-Mersey, England, assignor to The Churchill Machine Tool Company Limited, Broadheath, near Altrincham, England, a British company

Application March 21, 1938, Serial No. 197,268
In Great Britain March 31, 1937

5 Claims. (Cl. 125—11)

This invention relates to grinding wheel truing devices for grinding or abrading machines, the grinding wheel having an operative face of circular or other form such as is requisite, for example, for grinding the races of ball type journal bearings and thrust races.

The object of the present invention is to provide an improved arrangement of the truing device in the machine and improved means for bringing such device into operation and causing it to produce the desired contour on the grinding wheel.

The invention consists in a grinding wheel truing device carried upon the worktable of a grinding machine, the device being put into and out of service by a movement transversely to the direction of the worktable, and being moved in an arc of a circle to give the correct wheel contour by stopping the movement of one of two intergeared or interconnected parts.

The invention comprises a slide upon the worktable capable of movement transversely to the direction of movement of the worktable, and a second slide upon the above said slide capable of movement in the direction of movement of the worktable, means moving the first slide towards the grinding wheel as the workpiece moves on its way to the grinding position, means for arresting the motion of the second slide so that the one slide then moves relatively to the other, means utilizing said relative movement to cause the wheel truing tool to move through the correct path for truing the grinding wheel before it engages the workpiece, and means returning the first slide to its initial position to put the truing tool out of service.

Referring to the accompanying explanatory drawings:

Figure 1 is a plan view, Figure 2 a cross sectional view on the line 2—2 of Figure 1, and Figure 3 a sectional view on the line 3—3 of Figure 2 illustrating part of a grinding machine with wheel truing means in accordance with this invention.

Figure 4 is a side view, Figure 5 a plan and Figure 6 an end view illustrating a modification wherein the truing tool is constrained to move in a definite path by a former to produce the desired contour on the grinding wheel.

The table *a* upon which the work headstock *b* carrying the revolving work holder *c* is mounted and which is moved towards the grinding wheel *d* to cause the latter to engage the workpiece *e* which may be a ball race, carries a slide *f* which

is bolted to the table *a* by the bolts *g* where required.

Upon the slide *f* is a second slide *h* which can be traversed back and forth upon the slide *f* by the hydraulic plunger *i*. The slide *h* has thereon a top slide *j* which can be secured thereto in any position of adjustment. Such top slide comprises a bracket *k* upon a vertical face of which is traversible a slide *m*. The latter has a swivel bracket *n* journaled therein, such bracket carrying at its upper end the diamond truing tool *o* and at its lower end the pinion *p* which engages the rack *q* upon the slide member *j*. A spring *r* in the bracket *k* tends to force the slide *m* to the right in Figure 1 and an abutment *s* upon a bracket *t* on the grinding wheel head arrests the motion of the slide *m* in a direction towards the grinding wheel head. If the slide *m* ceases to move, but the slide *k* continues to move towards the grinding wheel head, then the rack *q* will turn the pinion *p* and so the swivel bracket *n* and truing tool *o* about the axis of the swivel bracket which will cause the tool to true the grinding wheel to the correct peripheral contour.

The action of the mechanism is as follows:—
The worktable *a* moves towards the grinding position, carrying with it the slide *f* and the parts and slides *h* and *j* and *m* thereon. The cross traversing slide *h* is advanced by the hydraulic plunger *i* and brought against a micrometer stop *u*. When the diamond truing tool *o* is in position to commence truing the grinding wheel *d*, the spring loaded slide *m* has its motion arrested by the fixed stop or abutment *s*, which results in the diamond truing tool holder being turned through an arc of a circle about the axis of the swivel bracket *m* by the rack *q* and pinion *p* so that truing of the grinding wheel with a correct circular contour is ensured. When truing is completed, the hydraulic pressure holding plunger *i* with the cross traversing slide *h* against the micrometer stop *u* is released, allowing such slide to return under the pressure of the spring *w*. The slide *m* at the same time moves clear of the stop or abutment *s* and returns to its initial position, which causes the diamond tool holder also to return to its initial position. The wheel truing equipment is now ready for the next wheel truing cycle. The worktable *a* continues to move to the grinding position, when its motion is arrested for the actual grinding operation.

In the modification shown in Figures 4, 5 and 6, the truing tool *o*¹ is carried in a member *n*² pivotally mounted upon a pin *z* secured in the swivel bracket *n*¹. The pivoted member *n*² acts

against the pressure of a spring 3 and carries in its rear a part 4 which rides upon a former 5 secured upon the slide n^1 .

In operation, when the slide m^1 is arrested as described in connection with the previous form of the invention, the swivel bracket n^1 is turned by the rack q^1 on the slide j^1 and the pinion p^1 . This results in the truing tool o^1 being turned through an arc of a circle about the axis of the swivel bracket n^1 , and at the same time receiving a movement from the former 5 towards or away from the axis of the grinding wheel d^1 . The above two movements combine to cause the tool o^1 to give the correct peripheral contour to the grinding wheel.

The present invention may be applied to the machine described in prior Patent No. 2,005,332, or to other types of internal or external grinding machines.

20 What I claim is:

1. A grinding wheel truing device for a grinding or abrading machine comprising a worktable movable towards and from the grinding wheel, a slide upon the worktable capable of movement transversely to the direction of movement of the worktable, and a second slide upon the aforesaid slide capable of movement in the direction of movement of the worktable and spring impelled in the direction towards the grinding wheel, 25 means automatically moving the first slide towards the axis of the grinding wheel as the workpiece moves on its way to the grinding position, means for arresting the motion of the second slide as it is carried with the worktable in the direction towards the grinding wheel so that the first slide then moves relatively to the second slide, means utilizing said relative movement to cause the wheel truing tool to move through the correct path for truing the grinding wheel before 35 it engages the workpiece, and means returning the first slide to its initial position to put the truing tool out of service.

2. A grinding wheel truing device for a grinding or abrading machine having a worktable 45 movable towards and from the grinding wheel, comprising a main slide fixed to but adjustable along the worktable, a further slide, capable of movement upon the main slide transversely to the direction of movement of the worktable, an 50 additional slide adjustable upon the further slide in the direction of movement of the latter, a

still further slide movable upon the additional slide in the direction of movement of the worktable, a swivel bracket carrying the wheel truing tool mounted upon a vertical axis upon the said still further slide, a pinion secured to said swivel bracket coaxially therewith, a rack upon said additional slide engaged by said pinion, a spring to move the still further slide in the direction towards the grinding wheel and a stop or abutment to arrest its movement when the worktable is carrying the main slide towards the grinding wheel head, automatic means to move the further slide to cause the truing tool to engage the grinding wheel as the worktable moves towards the grinding wheel and the still further slide to come into 15 the path of the stop or abutment, and automatic means to return the said further slide to its initial position after the truing operation.

3. A grinding wheel truing device as claimed in claim 1 having a swivel bracket upon said second slide, means actuated by relative movement between said first and second slides to turn said swivel bracket, a pivotal member upon said swivel bracket, a grinding wheel truing tool upon said pivotal member, a spring acting upon said pivotal member to move said tool away from the grinding wheel, a cam track upon said first slide and a cam track follower upon said pivotal member moving over said cam track as said swivel member turns to move said truing tool towards the 30 grinding wheel as required.

4. A grinding wheel truing device as claimed in claim 2 having a swivel bracket upon said still further slide, means actuated by relative movement between said further and still further slides 35 in turn said swivel bracket, a pivotal member upon said swivel bracket, a grinding wheel truing tool upon said pivotal member, a spring acting upon said pivotal member to move said tool away from the grinding wheel, a cam track upon said further slide and a cam track follower upon said pivotal member moving over said cam track as said swivel member turns to move said truing tool towards the grinding wheel as required.

5. A grinding wheel truing device as claimed in claim 2 wherein said truing tool is mounted in a part of said swivel bracket off-set from the axis of said swivel bracket and is adjustable towards and from said axis.
